COMBINED TIRE GAUGE AND MARKER

Orlando A. Malanga, 4201 Montalvo St.,
San Diego, Calif. 92107

Filed July 31, 1967, Ser. No. 8,055

Term of patent 14 years

(Cl. D52—6)

FIGURE 1 is a side elevational view of a combined tire gauge and marker, showing my new design.

FIGURE 2 is a side elevational view ninety degrees from that of FIGURE 1. The opposite side is the same.

FIGURE 3 is a side elevational view opposite to that of FIGURE 1.

FIGURE 4 is an end view thereof from the end opposite the marking point.

FIGURE 5 is a side elevation viewed from the same position as that of FIGURE 3 with indicator retracted and marking point extended.

The dominant features of my design reside in the full line portions shown.

I claim:

The ornamental design for a combined tire gauge and marker, as shown and described.
